UNITED STATES PATENT OFFICE.

MILLARD F. BLAKE, OF MARTINSBURG, PENNSYLVANIA.

DUMPING-CAR.

SPECIFICATION forming part of Letters Patent No. 635,646, dated October 24, 1899.

Application filed August 17, 1899. Serial No. 727,518. (No model.)

To all whom it may concern:

Be it known that I, MILLARD F. BLAKE, a citizen of the United States, residing at Martinsburg, in the county of Blair and State of Pennsylvania, have invented certain new and useful Improvements in Dumping-Cars; and I do declare the following to be a full, clear, and exact description of the invention, such as will enable others skilled in the art to which it appertains to make and use the same.

My invention relates to dumping-cars, and more particularly to that class of which the Patent No. 567,019, granted to me September 1, 1896, may be taken as a type; and the object is to improve the construction and increase the efficiency of the car.

To this end the invention consists in the construction, combination, and arrangement of the several elements of the device, as will be hereinafter more fully described and claimed.

In the accompanying drawings the same reference characters indicate the same parts of the invention.

Figure 1 is a perspective view of my improved dumping-car. Fig. 2 is a top plan view of the same. Fig. 3 is a longitudinal section. Fig. 4 is a transverse central section on the line 4 4 of Fig. 2. Fig. 5 is a similar view taken on the line 5 5 of Fig. 2.

11 denote the parallel fixed sides, and 22 the corresponding ends of the car-body.

33 denote the bolsters to which the trucks (not shown) are pivoted, and 44 denotes a central longitudinal beam extending the entire length of the car, its ends being fixed to and braced with the end of the car-body and also to the intersecting portions of the bolsters on which it rests.

66 designates a central transverse beam resting on the said longitudinal beam and having its ends suitably braced in the side walls of the car.

77 denote the tilting bottom sections fulcrumed on the cross-rods 88 and provided with the hinged end sections 99, which incline upwardly and outwardly and have their upper ends resting against the end walls of the car, and each is provided with an outwardly-projecting flange 10, which overlaps or extends over the upper edge of the con-

tiguous end wall to prevent the coal from getting in between the hinged and the fixed walls.

The meeting ends of the tilting bottom sections are bifurcated to straddle the longitudinal beam and the extension-pieces 1212, fixed 55 to the top edge of said beam and extending on each side of the transverse beam, and the upper edges of these extension-pieces and likewise the transverse beam are beveled off on each side of the central line and also overlap the contiguous edges of the tilting bottom sections to prevent any coal lodging on the extension-pieces or cross-brace or finding its way in between them and the bottom sections.

1313 denote inclined ridge-pieces fixed to 60 the inside face of the side walls, so as to project over the contiguous edges of the bottom sections to cover the joints formed between the side walls and the sides of the forward ends of the bottom sections.

14 denotes a chain stay or brace connecting the sides of the car-body to prevent lateral bulging, and 15 denotes a longitudinal truss-brace, which forms a central support for the longitudinal beam.

1616 denote rack-bars fixed to the side of the car to support the cross-rods 1717, which in turn support the meeting ends of the tilting sections. These rods are provided with pinions, which mesh with the racks and also 75 with a hand-wheel for manipulating them. The upper faces of the bottom sections, the inner faces of the hinged end walls, and the upper edges of the transverse brace, the extension-pieces, and the ridges are all covered 80 with sheet metal to protect them, and this sheet-metal lining also presents a smooth surface to facilitate the discharge of the coal.

It will of course be understood that various changes in the form, proportion, and the minor details of construction may be resorted to without departing from the principle or sacrificing any of the advantages of this invention.

Having thus fully described my invention, 95 what I claim as new and useful, and desire to secure by Letters Patent of the United States, is—

In a dumping-car provided with tilting bottom sections, the combination with the cen- 100

tral longitudinal beam, the extension-pieces fixed thereto, the transverse beam interposed between said extension-pieces and the inclined ridge-pieces 13 fixed to the side walls 5 of the car-body and projecting over the contiguous edges of the bottom sections, substantially as and for the purpose set forth.

In testimony whereof I have hereunto set my hand in presence of two subscribing witnesses.

MILLARD F. BLAKE.
